DRAIN

Robert H. Shenk, Erie, Pa., assignor to J. A. Zurn Manufacturing Company, Erie, Pa., a corporation of Pennsylvania

Application March 11, 1939, Serial No. 261,391

9 Claims. (Cl. 182—31)

This invention relates generally to surface drains, and more particularly to drains which prevent refuse and the like from passing to the main drain line to which the drain is connected.

5 Drains of this general character made according to the teachings of the prior art, and with which I am familiar, have had very inefficient means for metering the water after the drain became clogged in order to give notice that the 10 drain was clogged. These devices either gave no notice whatsoever or they became entirely clogged and caused a flooded condition around the surface being drained. None of the covers in these prior devices provided means for metering the liquid to be drained nor did the covers provide means for directing the flow of liquid to the center of the restraining means or bucket.

It is accordingly, an object of my invention to overcome the above and other defects in drains 20 and more particularly to provide a drain which is simple in construction, efficient in operation, cheap in cost, and easy to install.

Another object of my invention is to provide a surface drain wherein means are provided for 25 indicating the clogging of the straining member of the drain without flooding the drained surface.

Another object of my invention is to provide a surface drain which has a cover designed to meter the flow of fluid to the drain and to direct 30 the drained water to the central portion of the drain structure.

Another object of my invention is to provide a simple means for removing the strained refuse from the drain.

35 Another object of my invention is to provide a surface drain which has all parts thereof removable through the inlet opening.

Another object of my invention is to provide a surface drain wherein the parts thereof are so 40 disposed that a metering aperture is provided to restrain solids but permitting a predetermined flow of fluid therethrough.

Another object of my invention is to provide a surface drain wherein the metering aperture is 45 below the surface of the drain cover and is protected by the initial straining means or perforated cover.

Other objects of my invention will become evident from the following detailed description, 50 taken in conjunction with the accompanying drawing, in which

Fig. 1 is a plan view with parts broken away of my novel surface drain.

55 Fig. 2 is a side elevational view with parts

broken away of my novel surface drain connected to a drain line.

Referring to the drawing, my novel surface drain comprises generally an outer cylindrical member 1 having an inlet and an outlet, a solids retaining member 2, and a cover 3 having tapered slots 4. The outer cylindrical member 1 has an offset portion 5 providing a shoulder 6. An outwardly and upwardly extending portion 7 with a plurality of projecting members 8 provide anchoring means for the drain and furthermore directs the seepage into the drain line through the apertures 9 in the cylindrical member 1. The bottom portion 10 of the cylindrical member 1 is flanged inwardly and an interiorly threaded aperture 11 is formed to engage a drain line 12 to drain the liquid from the surface of the floor to be drained.

The solids retaining member 2 is cup-shaped in form and the sides thereof have apertures 13 to 20 permit the lateral flow of fluid passing through the drain while retaining the solids in the solids retaining member 2. A few small apertures 14

are disposed in the bottom of the solids retaining member 2 to permit better flow of fluid through 25 the drain. The solids retaining member 2 is disposed in spaced relation with the side and bottom portions of the cylindrical member 1 by means of annular ring member 15 and brackets 16 connecting the ring member 15 and the outer surface of the solids retaining member 1. The annular ring member 15 rests on the shoulder 6 of the cylindrical member 1 and supports the solids retaining member 2 in spaced relation with the sides and bottom of the cylindrical member 1. A 30

slotted cover 3 has a wide rim or border portion 17 extending to the interior surface of the solids retaining member 2 in order that the fluid will 35 not flow directly to the drain line 12 without passing through the solids retaining member 2. 40

An annular shaped aperture 18 is provided between the bottom portion of the cover 3 and the top of the retaining member 2 in order that the fluid may pass to the drain line 12 when the apertures 13 of the solids retaining member 2 45 becomes clogged. The width of this aperture 18 is such that a noticeable amount of fluid will be backed up to noticeably cover the slotted cover 3 in order that notice may be given that the solids retaining member 2 is clogged and must be removed. The annular aperture 18 is protected by 50 the cover 3 and is such width that ordinary solids will not pass therethrough. The tapered slots 4 in the cover 3 tend to direct the fluid passing into the drain directly to the center of 55

the solids retaining member 2 thereby increasing the efficiency of the solids retaining member 2 in that the solids will strike an unperforated portion of the solids retaining member 2 and the fluid 5 will move outwardly laterally therefrom. By removing the cover 3, it will be evident that the solids retaining member 2 may be very simply removed.

In operation, the tapered slots 4 in the cover 3 10 causes the fluid entering the drain to flow to the center of the solids retaining member 2 wherein it flows laterally outwardly through the apertures 13, the solids being retained in the solids retaining member 2. When the apertures 13 of 15 the solids retaining member 2 become clogged, the fluid will overflow the solids retaining member 2 and pass through the annular aperture 18 to the drain line 12. The annular aperture 18 will not permit solids to pass therethrough and it will further cause the backing up of the fluid so that it 20 will overflow the cover 3 and give notice that the apertures 13 are clogged and that the solids retaining member 2 must be removed. The removal of the solids retaining member 2 is evident from inspection of the drawing.

It will be evident that I have provided a surface drain which is simple in construction, easy to clean, efficient in operation, and operable after clogging of the solids retaining member 2 with 30 means for giving notice of the clogged condition of the retaining member.

Various changes may be made in the specific embodiment of the present invention without departing from the spirit thereof, or from the scope 35 of the appended claims.

What I claim is:

1. A surface drain of the class described, in combination, a member having an inlet and an outlet, a solids retaining member disposed centrally of said first mentioned member having the sides thereof perforated to permit the lateral flow of fluid, a slotted cover for said first mentioned member disposed to provide an annular aperture between the top of the solids retaining 45 member and said cover whereby fluid may pass therethrough to the outlet of said first member when said solids retaining member becomes clogged.

2. A surface drain as set forth in claim 1 50 wherein the slots in said cover are tapered to direct the fluid to the center of said solids retaining member.

3. A surface drain as set forth in claim 1 wherein said first mentioned member has an 55 outwardly extending flange to direct seepage to said outlet of said first mentioned member.

4. A surface drain of the class described, in combination, a cylindrical member having an inlet and an outlet, a solids retaining member disposed in said cylindrical member in spaced relation with the sides thereof, and a slotted cover having a wide rim portion whereby fluid can pass only to said solids retaining member, said cover and said solids retaining member being disposed to provide an annular aperture for the flow of fluid to said outlet of said cylindrical member when said solids retaining member becomes clogged.

5. A surface drain of the class described, in

combination, a cylindrical member having an inlet and an outlet, a cup-shaped solids retaining member disposed centrally of said cylindrical member and in spaced relation thereto, the sides thereof being perforated, and a perforated cover disposed over the inlet of said cylindrical member to direct the fluid to the center of said solids retaining member and to form an annular aperture between the top of said solids retaining member and said cover whereby fluid 10 may flow therethrough to said outlet when the perforations in said solids retaining member become clogged. 5

6. In a surface drain, in combination, a cylindrical member having an inlet and an outlet, said cylindrical member having the upper portion thereof offset to form a shoulder, a solids retaining member having outwardly projecting portions engaging said shoulder of said cylindrical member to support said solids retaining member in spaced relation with said cylindrical member, and a perforated cover carried by said outwardly projecting portion of said solids retaining member disposed to direct all fluid into said solids retaining member, said cover and the top 25 of said solids retaining member forming an annular aperture whereby fluids may flow therethrough to said outlet when the apertures in said solids retaining member become clogged.

7. A surface drain as set forth in claim 6 30 wherein the slots in the cover are tapered to direct the fluid to the center of said solids retaining member.

8. In a surface drain, in combination, a cylindrical member having an inlet and an outlet and an inner shoulder on the upper portion thereof, a solids retaining member having perforated sides and an outwardly projecting portion for engaging said shoulder to support said solids retaining member in spaced relation with the interior of said cylindrical member, and a wide rimmed cover having slots therein disposed over the inlet of said cylindrical member, the wide rimmed portion of said cover and the top of said solids retaining member forming an annular aperture for the flow of fluid to said outlet of 40 said cylindrical member when the perforations of said solids retaining member are clogged while retaining solids in said solids retaining member. 45

9. In a surface drain, in combination, a cylindrical member having an inlet and an outlet and an inner shoulder on the upper portion thereof, a solids retaining member having perforated sides and an outwardly projecting portion for engaging said shoulder to support said solids retaining member in spaced relation with the interior of said cylindrical member, and a wide rimmed cover having slots therein disposed over the inlet of said cylindrical member, the rim portion of said cover being disposed to direct 60 fluid into said solids retaining member and forming with the top of said solids retaining member an annular aperture for the flow of a predetermined amount of fluid to said outlet when the perforations of said solids retaining member are 65 clogged while backing enough fluid to give notice that the perforations are clogged.

ROBERT H. SHENK.
